SHEET CONVEYING DEVICE FOR PRINTING MACHINES

Primo Radice, Milan, Italy, and Hermann Schwerdt, Berlin-Falkensee, Germany, assignors to the firm Adrema Maschinenbauges m. b. H., Berlin, Germany

Application October 26, 1937, Serial No. 171,128
In Germany October 15, 1936

9 Claims. (Cl. 101—57)

Our invention relates to conveying means for printing machines of the type principally used for the printing of addresses and equipped with a printing mechanism and with mechanism for moving printing plates past a printing station in their longitudinal direction.

While in address-printing machines in which the printing plates are conducted across the table of the machine from the rear longitudinal side of the table, there is no difficulty about arranging the said conveying means, since the strip-like sheets or the like which are to be printed, are conveyed from one longitudinal side of the table to the other, and printed at the printing station with several impressions arranged in sequence in the longitudinal direction of the sheets, the arrangement is difficult in machines in which the printing plates are conducted one behind the other from one transverse side of the table to the other, because the supply container for the printing plates projects from the table in the vicinity of one of the transverse sides.

It is an object of our invention to provide conveying means suitable for the last-mentioned type of machine.

Heretofore, it has been attempted to solve the problem underlying the invention by conducting the sheets to be provided with the several impressions in the longitudinal direction of the machine table, i. e., above the track of the printing plates. This involves the drawbacks that the sheets completely conceal the printing plates and that it is necessary to conduct the sheets above the supply container for the printing plates.

A solution which does not involve the aforesaid drawbacks is provided by our invention in which the sheets are delivered from a container for a supply of sheets arranged at or near the front longitudinal side of the table, to conveyer belts arranged at right angles to the direction in which the printing plates move until the sheet which is on the conveyers at the time and advances toward the printing station with one of its longer sides leading, is arrested by a movable check, or preferably, a pair of checks. The first impression is now made on the sheet and thereupon the sheet is shifted longitudinally by intermittently operating means until all impressions have been made side by side on the sheet. The check, or checks, is now withdrawn and at the same time the sheet is engaged by clamping means holding it against the conveyers, and ejected. Automatic means which may be connected to the sheet-delivering means, are pro-

vided for alternately placing into active position the check and the clamping means.

Other advantages of our novel feeding device are that it does not require any extra space in the longitudinal direction of the machine so that it can be adapted to the table of a normal printing machine; that it can be made as a unit which is readily attached to, and detached from, the table of an existing printing machine; and that its construction is quite simple.

In the accompanying drawings, two machines embodying our invention are illustrated by way of example.

In the drawings

Fig. 1 is a perspective illustration of a machine in which two checks for arresting the sheets at a printing station are mounted to oscillate about a shaft.

Figs. 2 and 3 are details of the machine in Fig. 1 showing, respectively, one of the checks in active, and the corresponding clamping means in inactive position, and vice versa; and

Fig. 4 is a perspective illustration showing part of a machine which is similar to the one shown in Fig. 1 but in which one of the checks is secured to a spring, and controlled by the means for shifting the sheets.

Referring now to the drawings, and first to Figs. 1 to 3, 1 is a table of the machine, and 9 is its front longitudinal side. 2 is the printing arm, and 4 is a hopper on the table 1 for the reception of a supply of printing plates 3. The mechanism by which the printing arm is reciprocated, and the mechanism by which the printing plates 3 are moved in their longitudinal direction and transversely to the sides of the table 1, as indicated by arrow 5 in Fig. 1, past a printing station 6, will not be described as they form no part of the present invention.

A supply of sheets 7 to be printed is stored in a container arranged at the front side 9 of the table 1, with a front plate A and a side wall 8. The machine is supposed to be an address-printing machine and each sheet 7 is to receive three impressions at I, II, and III so that each plate 3 to be printed remains at the station 6 during the making of these three impressions.

Arranged before the front plate A of the supply container are a pair of delivering rollers 10 on a shaft 40 mounted to rotate in a pair of brackets at the sides of the supply container. Rotation in the direction of arrows 41 is imparted to the shaft 40 by any suitable means, not shown.

A cylinder 14 is rotatably mounted below the delivering rollers 10 and partly projects from the

table 1. Four endless conveyer belts 11, 12, 26, and 27 are placed about the cylinder 14—and a corresponding cylinder, not shown, at the opposite end—and their upper reaches move in the direction of arrows 13 at right angles to the direction 5 in which the printing plates 3 move toward the printing station 6.

The foremost sheet 7 in the supply container is delivered to the three belts 11, 12, and 26, and 10 conveyed to the printing station 6 with the assistance of suitable rollers 15, 16, 16' above the belts. At the printing station, where it assumes the position 7', the sheet is arrested by a fixed stop 18 and a pair of movable checks 19. At the 15 same time, the delivering rollers 10 are stopped by any suitable means, not shown, so that the subsequent sheet from the supply container is not engaged for the present.

The movable checks 19 against which the sheet 20 in the position 7' abuts with its leading edge 17, this being one of its longer sides, are secured to a bar 20 which has eyes 20' at opposite ends by which it is mounted to oscillate about a shaft 22 mounted in a pair of brackets 23 on the table 1. 25 Keyed on the shaft 22 in the vicinity of the bracket 23 at the right is a crank 28 whose crank pin 28' engages a substantially triangular member 29 with a slot 31. A pin 29' connects this member 29 to an arm 30 which is an extension of the eye 20' at the right of the bar 20, its slot 31 clearing the shaft 22. Secured to the member 29 is a push rod 32 at its front end. The rear end of the push rod 32 is pivotally connected to an arm 35 on a shaft 36 mounted to rotate on the 30 table 1. A spring 34 tends to pull the push rod 32 against the arrow 33. 37 is a lever on the shaft 36, 38 is a roller on the free end of the lever, and 39 is a cam on the shaft 40 of the delivering rollers 10 for cooperation with the roller 38. The 40 central portion of the shaft 22 is a bar 24, of square cross-section, and on the bar are mounted the brackets of three rollers 25 for clamping the sheets against the belts 13, 26, and 27, respectively.

45 The intermittently operating means for shifting the sheets longitudinally will now be described. Mounted to rotate on suitable brackets on the table arranged between the belts 11 and 12, and at the right of the belt 27, are short shafts 50 44. Keyed on the shaft which is between the belts 11 and 12 is a sector 42, and keyed on the other shaft is a sector 43, with backing rollers 49 and 50, respectively. 46 is a shaft mounted in the brackets, 45 are bevel gearings connecting it 55 to the sector shafts 44, and 47 is a cord pulley, or sprocket, for rotating the shaft 46.

The sectors 42 and 43 may be so designed that they can be adjusted radially and/or axially, and they may be disks with sheet-engaging portions 60 projecting from the rim of the disk, as will be described with reference to Fig. 4.

The operation of the conveying device is as follows: A sheet 7 delivered from the supply container by the rollers 10 is engaged by the belts 11, 65 12, and 26 and the corresponding rollers 15, 16, and 16', and conveyed to the printing station 6 where it occupies the position 7', with its leading edge 17 abutting against stop 18 and checks 19, as described. The sector 42 is elevated at the 70 time and so does not interfere with the advancing sheet. The checks 19 are on the table, and the clamping rollers 25 are in elevated position, as shown in Fig. 2. The delivering rollers 10 are stopped, the printing arm 2 descends and makes 75 the first impression at I. The sector 42 has con-

tinued its rotation in the direction of the arrow 48 until it engages the sheet between its rim and the backing roller 49, and shifts it in the direction of arrow 51. The second impression is now made at II and, after another operation of the sector 42 assisted by the sector 43 and its backing roller 50, the third impression is made at III. The finished sheet occupies the position 7'', its leading edge 17 clearing the stop 18 and the belt 11 but not the checks 19. The delivering rollers 10 are 10 re-started, and the cam 39 on its shaft 40, through roller 38, arm 37, shaft 36, and push rod 32 which is moved in the direction 33 against spring 34, through the member 29 and the crank 28 lifts the checks 19 away from the table and 15 depresses the three rollers 25, as shown in Fig. 3, so that the sheet is now clamped between the belts 12, 26, and 27, and the corresponding clamping rollers, and ejected in the direction of arrow 52. 20

Referring now to Fig. 4, the general arrangement of this machine is quite similar to the one described with reference to Figs. 1 to 3, but the shifting sectors are modified. Only the sector 48' at the right is shown but it is understood that 25 the sector at the left is quite similar.

This "sector" is, properly speaking, a disc with a sector-shaped rib 50 extending over part of its rim. Its position is also different in that it is between the belt 26 and 27, and not at the right of 30 belt 27, as in Fig. 1.

Only the check 19 at the left is provided here and is controlled by the push rod 32, as described. Instead of the check at the right, a check plate 53 is secured to a spring 54. The spring, in turn, 35 is attached to an angle bar 56 on the table 1 to which also the spring 34 of the push rod 32 is anchored. The spring tends to hold the check plate 53 down against the table 1. At the rear end of the spring plate 53, a slotted guide 56 is 40 provided. In this guide engages a pin at the lower end of a slide 57 which is placed on an extension 59 of the sector shaft 40 with a slot 58. At its upper end, another pin 60 is arranged for co-operation with a cam 61 on the shaft extension 45 59.

While normally the check plate 53 holds the sheet 7 in the corresponding printing position, it is elevated during each revolution of the sector in the direction of the arrow, when the sheet 7 is to 50 be shifted in the direction of arrow 51, or the finished sheet is ejected in the direction of arrows 13 and 52, exactly as in the machine described with reference to Fig. 1.

We claim:

1. In a sheet-conveying device for printing machines which are equipped with a printing mechanism and with mechanism for moving printing plates past a printing station in their longitudinal direction; a table, a container for a supply of sheets on the table, conveyer belts arranged with their upper reaches above the table and at right angles to the direction in which the printing plates move, means for moving the upper reaches from the supply container toward the printing 65 station, means for delivering a sheet at a time from the supply container to the upper reaches of the belts with one of its longer edges leading, a movable check for arresting the sheet when it has arrived at the printing station where the first 70 impression is made, intermittently operating means for shifting the sheet longitudinally until all impressions have been made thereon, movable means for clamping the finished sheets against certain belts, and automatic means for 75

alternately placing into active position the check and the clamping means.

2. In a sheet-conveying device for printing machines which are equipped with a printing mechanism and with mechanism for moving printing plates past a printing station in their longitudinal direction; a table, a container for a supply of sheets on the table, conveyer belts arranged with their upper reaches above the table and at right angles to the direction in which the printing plates move, means for moving the upper reaches from the supply container toward the printing station, means for delivering a sheet at a time from the supply container to the upper reaches 10 of the belts with one of its longer edges leading, a movable check for arresting the sheet when it has arrived at the printing station where the first impression is made, intermittently operating means for shifting the sheet longitudinally until 15 all impressions have been made thereon, movable means for clamping the finished sheets against certain belts, and means operatively connected to the sheet-delivering means for alternately placing into active position the check and the clamping 20 means.

3. In a sheet-conveying device for printing machines which are equipped with a printing mechanism and with mechanism for moving printing plates past a printing station in their longitudinal 30 direction; a table, a container for a supply of sheets on the table, conveyer belts arranged with their upper reaches above the table and at right angles to the direction in which the printing plates move, means for moving the upper reaches from the supply container toward the printing 35 station, means for delivering a sheet at a time from the supply container to the upper reaches of the belts with one of its longer edges leading, a movable check for arresting the sheet when it has arrived at the printing station where the first 40 impression is made, sectors for intermittently shifting the sheet longitudinally until all impressions have been made thereon, movable means for clamping the finished sheets against certain belts, 45 and automatic means for alternately placing into active position the check and the clamping means.

4. In a sheet-conveying device for printing machines which are equipped with a printing mechanism and with mechanism for moving printing plates past a printing station in their longitudinal direction; a table, a container for a supply of sheets on the table, conveyer belts arranged with their upper reaches above the table and at right 50 angles to the direction in which the printing plates move, partly below the supply container and partly at one side thereof, means for moving the upper reaches of all belts in the direction from the supply container toward the printing station, means for delivering a sheet at a time from the supply container to the upper reaches of the belts below the container, with one of its longer edges leading, a movable check for arresting the sheet 55 when it has arrived at the printing station where the first impression is made, intermittently operating means for shifting the sheet in the direction away from the belts which are below the container, until all impressions have been made on 60 the sheet, movable means for clamping the finished sheets against certain belts, and automatic means for alternately placing into active position the check and the clamping means.

5. In a sheet-conveying device for printing machines which are equipped with a printing mech-

anism and with mechanism for moving printing plates past a printing station in their longitudinal direction; a table, a container for a supply of sheets on the table, conveyer belts arranged with their upper reaches above the table and at right angles to the direction in which the printing plates move, means for moving the upper reaches from the supply container toward the printing station, means for delivering a sheet at a time from the supply container to the upper reaches of the belts with one of its longer edges leading, a fixed stop and a movable check arranged side by side for arresting the sheet when it has arrived at the printing station where the first impression is made, intermittently operating means for shifting the sheet longitudinally and clear of the fixed stop until all impressions have been made thereon, movable means for clamping the finished sheets against certain belts, and automatic means for alternately placing into active 20 position the movable check and the clamping means.

6. In a sheet-conveying device for printing machines which are equipped with a printing mechanism and with mechanism for moving printing plates past a printing station in their longitudinal direction; a table, a container for a supply of sheets on the table, conveyer belts arranged with their upper reaches above the table and at right angles to the direction in which the printing plates move, means for moving the upper reaches from the supply container toward the printing station, means for delivering a sheet at a time from the supply container to the upper reaches of the belt with one of its longer edges leading, a shaft mounted to rotate above the table at the rear of the printing station, a bar mounted to oscillate about the shaft, a check on the bar for arresting the sheet when it has arrived at the printing station where the first impression is made, intermittently operating means for shifting the sheet longitudinally until all impressions have been made thereon, rollers supported by the shaft for clamping the finished sheets against certain belts, and automatic means for turning the bar and the shaft in opposite directions, so as to alternately place into active 40 position the check and the rollers.

7. In a sheet-conveying device for printing machines which are equipped with a printing mechanism and with mechanism for moving printing plates past a printing station in their longitudinal direction; a table, a container for a supply of sheets on the table, conveyer belts arranged with their upper reaches above the table and at right angles to the direction in which the printing plates move, means for moving the upper reaches from the supply container toward the printing station, means for delivering a sheet at a time from the supply container to the upper reaches of the belts with one of its longer edges leading, a shaft mounted to rotate above the table at the rear of the printing station, a bar mounted to oscillate about the shaft, a check on the bar for arresting the sheet when it has arrived at the printing station where the first impression is made, intermittently operating means for shifting the sheets longitudinally until all impressions have been made thereon, rollers supported by 50 the shaft for clamping the finished sheets against certain belts, an arm projecting from the bar, a crank, projecting from the shaft in the direction opposite to that of the arm, a push rod, a member on the push rod pivotally connected to the 55

- arm and the crank, a cam operatively connected to the sheet-delivering means, and means operatively connected to the cam for operating the push rod.
5. In a sheet-conveying device for printing machines which are equipped with a printing mechanism and with mechanism for moving printing plates past a printing station in their longitudinal direction; a table, a container for a supply of 5 sheets on the table, conveyer belts arranged with their upper reaches above the table and at right angles to the direction in which the printing plates move, means for moving the upper reaches from the supply container toward the printing 10 station, means for delivering a sheet at a time from the supply container to the upper reaches of the belts with one of its longer edges leading, a movable check for arresting the sheet when it has arrived at the station where the first impression is made, a shaft mounted above the table 15 transversely to the belts, means for rotating the shaft, sector shafts, bevel gearing connecting each sector shaft to the transverse shaft, a sector on each sector shaft, and a backing roller for 20 each sector arranged in the table for intermittently shifting the sheet longitudinally until all impressions have been made thereon, movable means for clamping the finished sheets against certain belts, and automatic means for alternately placing into active position the check and 25 the clamping means.
9. In a sheet-conveying device for printing machines which are equipped with a printing mechanism and with mechanism for moving printing plates past a printing station in their longitudinal direction; a table, a container for a supply of 5 sheets on the table, conveyer belts arranged with their upper reaches above the table and at right angles to the direction in which the printing plates move, means for moving the upper reaches from the supply container toward the printing 10 station, means for delivering a sheet at a time from the supply container to the upper reaches of the belts with one of its longer edges leading, a movable check for arresting the sheet when it has arrived at the printing station where the first impression is made, rotary intermittently operating means for shifting the sheet longitudinally until all impressions have been made thereon, a check plate, a spring forcing the check plate against the sheet during the intervals of its intermittent 15 shifting movement, a cam operatively connected to the rotary shifting means, mechanism operatively connected to the cam for lifting the check plate from the sheet during its shifting movement, movable means for clamping the finished 20 sheets against certain belts, and automatic means for alternately placing into active position the check and the clamping means.

PRIMO RADICE.
HERMANN SCHWERDT.
